Sphere flight simulator google search; google.com; Oct. 27, 2021.*Primary Examiner — Mitchell I. Siegel(57) **CLAIM**

I claim the ornamental design for a flight simulator, substantially as shown and described.

DESCRIPTION

FIG. 01 is a front top-left perspective view of the flight simulator in accordance with the present design.

FIG. 02 is a back top-right perspective view of the flight simulator.

FIG. 03 is a front view of the flight simulator.

FIG. 04 is a back view of the flight simulator.

FIG. 05 is a top view of the flight simulator.

FIG. 06 is a bottom view of the flight simulator.

FIG. 07 is a left view of the flight simulator; and,

FIG. 08 is a right view of the flight simulator.

The broken line on the drawing figures form no part of the claimed design.
